Joseph Folk
By Nissen & Crane Atts.

UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA

SLICING MACHINE

Application filed November 8, 1926. Serial No. 146,919.

This invention relates to a machine for slicing meat or other commodities, and has for one of its objects the provision of a device for collecting the slices as they are formed in an orderly pile or stack.

A further object of the invention is to provide a machine of the class named which shall be of improved construction and operation.

10 Other objects will appear from the following description.

The invention is exemplified in the combination and arrangement of parts shown in the accompanying drawings and described in 15 the following specification, and it is more particularly pointed out in the appended claims. In the drawings—

Fig. 1 is a front elevation, with parts in section, showing a slicing machine having 20 one embodiment of the present invention applied thereto;

Fig. 2 is a rear elevation of the machine shown in Fig. 1;

Fig. 3 is a section substantially on line 25 3—3 of Fig. 1;

Fig. 4 is a section substantially on line 4—4 of Fig. 2;

Fig. 5 is a section substantially on line 5—5 of Fig. 4; and

30 Fig. 6 is a section on line 6—6 of Fig. 4.

The numeral 10 designates a base having a bracket 11 mounted thereon provided with a bearing 12 having a knife spindle 13 journaled therein. A disc knife 14 is carried by 35 the journal 13 and a pulley wheel 15 is fixed to the spindle and knife. The bracket 11 has a web or plate 16 integral therewith which forms a housing enclosing a belt 17 which passes over the pulley 15 and engages a second 40 pulley 18 mounted on a motor shaft 19. The motor shaft 19 is driven by a motor 20 mounted on the base 10. A plate 21 is secured to the rearwardly extending edge 22 of the web member 16 and covers the major portion of 45 the rear face of the knife 14. The knife 14 is provided with an offset shoulder 23 and one edge of the plate 21 is curved, as shown at 24, to fit within the shoulder 23 of the knife 14, the knife and plate being arranged 50 at a slight angle to one another to permit the

curved portion of the plate 21 to project into the recess formed by the shoulder 23, as shown in Figs. 2 and 3.

A housing member 27 is supported on the base 10 and is provided with a rear wall 28 which carries a plate 29 having a curved edge 30 disposed adjacent the exposed edge of the knife 14. An upright shaft 31 is journaled in brackets 32 formed on the wall of the housing member 27. The shaft 31 carries arms 33 which support a rod 34 pivotally connected with ears 35 formed on the wall 28. A link 36 is interposed between an ear 37 on the wall 28 and a bracket 38 on the housing member 27. The link 36 and the arms 33 form parallel motion mechanism for guiding the wall 28 and plate 29 to permit adjustment of the plate 29 relative to the cutting plane of the knife 14. To adjust the position of the plate 29 a hand wheel 39 is formed on a shaft 40 journaled in the housing 27 and provided with a worm 41 which meshes with a worm segment 42 on the shaft 31. A work support 43 is mounted to slide in the rear of the plates 29 and 21 in the direction of the cutting plane of the knife 14. The support 43, as shown in Fig. 2, is in the form of a trough having inclined side walls 44 and 45, the inner surfaces of which are provided with ribs or corrugations extending transverse to the cutting plane of the knife to reduce the friction of the material supported in the trough and permit easy movement thereof toward the knife. The work support 43 is mounted to slide on a guide rod 46 supported by posts 47 on the base 10. A second guide 48 is mounted beneath the guide rod 46 and engages a downwardly extending arm 49 for preventing rotation of the support about the guide rod 46. A handle 50 is secured to the support 43 for reciprocating the support on its guides.

A piece of material to be sliced is placed in the support 43 and the plate 29 is adjusted in front of the cutting plane of the knife 14 by an amount equal to the thickness of the slice desired. The knife is rotated by the motor 20 and the support 43 is moved along the guides 46 and 48 to cause the projecting portion of the material to engage the exposed edge of the knife 14 to sever the projecting

100

portion therefrom in the form of a slice. The support is then returned to a position registering with the plate 29 and the material is again moved forwardly until the surface from which the slice has been severed again engages the face of the plate 29. The movement of the support 43 is then repeated to sever another slice from the material in the support. This operation is repeated until the desired 10 number of slices has been formed or until the material has been as nearly completely sliced as possible with this form of apparatus.

In order to direct the slices as they are severed away from the slicing knife 14, a deflector 51 is arranged adjacent the front face of the slicing knife 14 so as to cover the larger portion of the cutting face of the knife. The edge of the deflector 51 is curved, as shown at 52, concentrically with 20 the edge of the knife and is spaced from the edge of the knife by a small amount sufficient to permit the knife to sever the slices from the body of the material in the support 43. The deflector plate extends backwardly 25 at an angle to the cutting plane of the knife and forms a housing enclosing the bearing 12, as shown in Fig. 3. The front edge of the deflector plate 51 is provided with ribs or corrugations extending in a substantially 30 horizontal direction to decrease the frictional resistance that the deflector offers to the slices. A slice receiver 53 is disposed beneath the deflector 51 and comprises an inclined plate 54 having an abutment 55 at 35 the end thereof toward which the slices are directed as they leave the slicing knife. A supporting plate 56 is arranged substantially normal to the inclined plate 54 and is carried by a bracket 57 projecting upwardly 40 through a slot 58 in the plate 54. It will be seen from the drawings that the plate 56 has its top inclined forwardly and also has the end thereof adjacent the abutment 55 inclined away from the deflector 51.

It will be understood that as the slice is directed away from the slicing knife by the deflector 51 the severed end of the slice will tend to move forwardly and downwardly and the inclination of the plate 56 is for the 45 purpose of providing clearance for the slice as it is projected in its natural course along the face of the plate 56. The slice as it is severed is suspended from its upper corner still attached to the body of the material being sliced. The momentum of the slice, together with the force exerted at the end thereof still attached to the body of the material, carries the slice along the plate 56 until such time as it is completely severed 55 from the piece, whereupon the slice falls forwardly upon the rear edge of the supporting plate 56 and lies with its broad side against the supporting plate. The deflector 51, of course, assists in directing the slice 60 away from the slicing knife and along the 65

plate 56. The deflector and plate are arranged in position to permit the slice to take substantially its natural direction under the forces of gravity and inertia and the supporting force due to the attachment of the slice to the unsevered body of the material. The slice is received in the position which it takes at the time that it is completely severed and is permitted to lie flat against the upper face of the plate 56. After each slice is deposited the plate 56 is fed downwardly and forwardly to provide space for additional slices.

The feeding mechanism comprises a screw 59 journaled in a bracket 60 which supports the lower end of the slice receiver 53. The upper end of the screw 59 is journaled in a bracket 61 mounted on the frame 10. A ratchet wheel 62 is secured to the upper end of the screw 59 and is operated by a pawl 63 pivoted on a lever 64. The bracket 61 carries a pin 65 which engages a stop 66 formed on the lever 64 for limiting rotation of the lever arm 64 in a clockwise direction, as viewed in Fig. 5. A spring 67 rotates the lever to bring the stop 66 against the pin 65. The lever 64 extends into the path of a roller 68 on an arm 69 projecting forwardly from the work support 43. The roller 68 engages the lever 64 after the slice has been severed and moves the lever to rotate the ratchet wheel 62 and the screw 59 to feed the plate 56 downwardly. A spring-held ball 70 is carried in a sleeve 71 formed at the lower end of the bracket 57 and surrounding the screw 59. The ball engages the threads of the screw 59 to feed the bracket downwardly when the screw 59 is rotated. In order to return the plate 56 to its initial or any desired position on the slice receiver it is only necessary to exert sufficient force on the plate to overcome the spring pressure on the ball 70 to cause the ball to ratchet over the threads on the screw 59. The contact faces of the plates 53 and 55 are corrugated, as shown in the drawings, to permit ready movement of a stack of slices as the plate 56 is fed downwardly.

I claim:

1. A slicing machine comprising a slicing knife and a work support, said work support being movable past the edge of said knife in a plane parallel to the plane of the edge of said knife for severing slices from material held by said support, a stationary slice receiver disposed at the side of said knife opposite said work support adapted to support the slices as they are being formed, a slice support mounted in said receiver, and means for feeding said slice support away from said knife to accommodate additional slices as they are deposited in said receiver.

2. A slicing machine comprising a slicing knife, a work support arranged to reciprocate past the cutting edge of said knife in a plane

parallel to the plane of the edge of said knife to sever slices from material held by said work support, a stationary slice receiver adapted to support the slices as they are being formed disposed at the side of said knife opposite said work support adjustable towards and away from the knife, and a slice support mounted on said slice receiver and disposed at an angle to the cutting plane of said knife.

3. A slicing machine comprising a slicing knife, a work support movable relative to the cutting edge of said knife for severing slices from material on said support, a slice receiver mounted in fixed position at the side of said knife opposite said work support, and a slice support mounted on said slice receiver, said slice support being inclined outwardly from the cutting plane of said knife at the side thereof toward which the slices move as they are severed by said knife.

4. A slicing machine comprising a slicing knife, a work support movable past the cutting edge of said knife to sever slices from material on said work support, a slice support disposed at the side of said knife opposite said work support, said slice support being inclined outwardly away from the cutting plane of said knife at the upper portion thereof and also at the side thereof toward which the slices are moved when severed by said knife, and means for adjusting said slice support away from the cutting plane of said knife along a fixed path to accommodate additional slices as they are formed.

5. A slicing machine comprising a slicing knife, a work support movable relative to the cutting edge of said knife to sever slices from material on said support, a slice receiving platform inclined downwardly away from the cutting plane of said knife, and a slice support movable along the upper face of said slice receiving platform, said slice support being inclined away from the cutting plane of said knife at the top thereof and also at the side thereof toward which the slices are moved as they are severed by said knife, and means for feeding said slice support away from the cutting plane of said knife to accommodate additional slices as they are formed.

6. A slicing machine comprising a slicing knife, a work support movable relative to the cutting edge of said knife to sever slices from material carried by said work support, a slice receiver disposed at the side of said knife opposite said work support and inclined downwardly away from said knife, an abutment plate at the side of said slice receiver toward which slices are moved when severed by said knife, and a slice support disposed above said slice receiver and inclined away from the cutting plane of said knife at the side of said slice receiver adjacent said abutment.

65 7. A slicing machine comprising a slicing

knife, a work support movable past the cutting edge of said knife to present material to said knife to sever slices from said material, a deflector inclined outwardly and backwardly from the cutting edge of said knife, and a substantially flat slice support spaced from said deflector and inclined outwardly and backwardly from the cutting plane of said knife.

8. A slicing machine comprising a slicing knife, a work support movable relative to said knife to present material to said knife to sever slices from said material, a deflector having one edge thereof disposed adjacent the cutting edge of said knife at the side of said knife opposite said work support, said deflector being inclined outwardly and backwardly from the cutting edge of said knife, the upper portion of said deflector being inclined outwardly a greater amount than the lower portion thereof, and a slice receiver spaced from said deflector and having the upper portion thereof inclined outwardly and also having the portion thereof toward which the slices move as they are severed inclined outwardly, said slice receiver being adapted to occupy a fixed angular position relative to the plane of said knife at all times.

9. A slicing machine comprising a slicing knife, a work support movable past the cutting plane of said knife, a slice deflector at the side of said knife opposite said work support having one edge disposed adjacent the cutting edge of said knife, said deflector being inclined outwardly and backwardly away from the cutting plane of said knife, a slice receiver inclined outwardly and downwardly below said deflector, and a slice support disposed above said slice receiver, said slice support being inclined outwardly and upwardly and also outwardly and backwardly from the cutting edge of said knife.

10. A slicing machine comprising a slicing knife having a substantially vertical cutting plane, a horizontally disposed work support movable past the cutting edge of said knife, a slice deflector at the side of said knife opposite said work support, said deflector being inclined outwardly and backwardly from the cutting edge of said knife and having the upper portion thereof inclined outwardly to a greater extent than the lower portion thereof, a slice support inclined outwardly and backwardly from the cutting edge of said knife, and means for feeding said slice support away from said deflector along a stationary path to accommodate additional slices as they are severed by said knife.

11. A slicing machine comprising a slicing knife having a substantially vertical cutting plane, a substantially horizontal work support movable past the cutting edge of said knife, a slice deflector disposed at the side of said knife opposite said work support, said deflector being inclined outwardly and back-

wardly from the cutting edge of said knife and also being inclined outwardly at the upper portion thereof, said deflector having restricted contact members for engaging the slices as they are severed by said knife, and a slice support spaced away from said deflector, said slice support being inclined away from the cutting edge of said knife and mounted to move only in a straight path towards and from said knife.

12. A slicing machine comprising a slicing knife having a substantially vertical cutting plane, a substantially horizontal work support movable past the cutting edge of said knife, a slice receiver at the side of said knife opposite said work support, said slice receiver being inclined outwardly and downwardly from the cutting plane of said knife, an abutment plate at the side of said receiver toward which the slices move as they are severed by said knife, a slice support movable over the surface of said slice receiver, and a deflector for directing slices onto said slice receiver against said slice support, said deflector and receiver having the surfaces thereof provided with restricted contact lines to diminish friction of the slices as they move along said surfaces.

13. A slicing machine comprising a slicing knife, a work support movable relative to the cutting plane of said knife, a stationary slice receiver disposed at the side of said knife opposite said work support, a slice support movable over the surface of said slice receiver, a feed screw for said slice support, and means operated by said work support for rotating said feed screw to move said slice support to accommodate additional slices as they are severed.

14. A slicing machine comprising a slicing knife, a work support movable past the cutting edge of said knife, a relatively fixed slice receiver disposed at the side of said knife opposite said work support, a slice support movable along the surface of said slice receiver, a feed screw for moving said slice support, pawl and ratchet mechanism for rotating said feed screw, and a contact member connected to said work support for operating said pawl and ratchet mechanism at each movement of said work support past the cutting edge of said slicing knife.

15. A slicing machine comprising a slicing knife having a substantially vertical cutting plane, a slice receiver disposed adjacent said slicing knife and inclined outwardly and downwardly therefrom, a slice support movable over the upper face of said slice receiver, an inclined feed screw for moving said slice support, and means for periodically rotating said feed screw.

16. A slicing machine comprising a slicing knife having a substantially vertical cutting plane, a substantially horizontal work support movable past the cutting edge of said

slicing knife, a deflector disposed at the side of said slicing knife opposite said work support and having one edge disposed adjacent the cutting edge of said slicing knife, said deflector being inclined outwardly and backwardly from the cutting edge of said knife and having its upper portion inclined outwardly beyond the lower portion thereof, a slice receiver below said deflector and inclined outwardly and downwardly from the cutting plane of said knife, an abutment plate at the side of said deflector toward which the slices move as they are severed by said knife, a slice support movable over the upper face of said slice receiver, said slice support being inclined outwardly at the upper portion thereof and also at the side thereof adjacent said abutment plate, an inclined feed screw for moving said support along said slice receiver, and means operated by said work support for periodically rotating said feed screw.

17. A slicing machine comprising a slicing knife, a work support arranged to move past the cutting edge of said knife to sever slices therefrom, and a substantially flat slice support inclined at an angle to the cutting plane of the knife in both a horizontal and vertical direction.

18. A slicing machine as claimed in claim 17 in which the slice support is movable in a direction substantially perpendicular to its vertical inclination to the cutting plane of the knife.

19. A slicing machine comprising a slicing knife, a work support movable past the cutting edge of said knife to present material to said knife so that it may cut slices from said material, a deflector inclined outwardly and backwardly from the cutting edge of the knife, and a slice support spaced from said deflector, said slice support being inclined in both a vertical and horizontal direction to the cutting plane of the knife, and movable only along a fixed path away from said knife.

20. A slicing machine comprising a slicing knife, a work support arranged to move relative to said slicing knife on one side thereof, a slice support arranged on the other side thereof adapted to move along a straight line bearing a fixed relation to the plane of said knife, said slice support being inclined in both a horizontal and vertical direction relative to the cutting plane of the knife.

21. A slicing machine as claimed in claim 20 in which a feeding means is provided to move the support along said straight line.

22. A slicing machine comprising a slicing knife, a work support arranged to move past the cutting edge of said knife to sever slices from material on said work support, and a slice support disposed at the opposite side of said knife from said work support, said slice support being inclined away from the cutting edge of said knife at the top there-

of and also at the side thereof toward which the slices are moved as they are severed by said knife, said slice support being adapted to move along a fixed path inclined to the 5 cutting plane of said knife.

In testimony whereof, I have signed my name to this specification on this fourth day of November, A. D. 1926.

JOSEPH FOLK.
